DES. 2073.

Ass't to

The Lowell Manufacturing Company, of the same place.

Letters Patent No. 2073 - Dated May 30, 1866.

Design for a Carpet Pattern.

The schedule referred to in these Letters Patent and making part of the same.

To all whom it may concern:

Be it known that I, Eliot J. Key, of Lowell, in the County of Middlesex and State of Massachusetts, have originated and designed a new Pattern for Carpets or other fabrics, of which the following is a full, clear and exact description, reference being had to the accompanying drawings, making part of this specification.

A is in the centre, is a group of flowers, leaves and sprigs.

B is a leaf resting on an eight pointed set figure, the particular form of it is shown in the drawing.

C is a scalloped shaped frame surrounding ground.

D. and resting on a wreath composed of flowers, leaves and sprigs.

E. F. on the sides are two halves, when matched will form the centre, the particular form of which is shown in the drawing 12.3.4. in the same quarter, when matched will form a cube like, E. F.

The colors employed for the different portions of the design, may be varied to suit the taste and wish of the manufacturer.

Claim

What I claim as my invention and desire to secure by Letters Patent, is the Design or Pattern for Carpets or other fabrics herein set forth.
